COUCH BED

Meyer Gursky, New York, N. Y.

Application August 24, 1940, Serial No. 354,059

3 Claims. (Cl. 5—31)

This invention relates generally to beds. More particularly my invention is directed to the type of twin couch or day bed disclosed in my Patent 2,133,167, dated October 11, 1938, for Couch bed.

One of the objects of the present invention is to provide a bed construction of the class described which shall be characterized by certain improved constructional features representing a general advance in the art of bed construction of the type disclosed in my said Patent 2,133,167.

Another object of my invention is to provide in a twin bed of the class described, an auxiliary section, foldable with respect to the main section and adapted to be raised or lowered therewith, in combination with novel automatic locking means designed to prevent damage to the bed.

Other objects of my invention will in part be obvious and in part hereinafter pointed out.

In the accompanying drawings,

Fig. 1 is a front elevational view of a bed constructed in accordance with my invention, with the auxiliary section in folded, ineffective position;

Fig. 2 is an end elevational view thereof as seen from the line 2—2 of Fig. 1;

Fig. 3 is a cross sectional view taken substantially on the line 3—3 of Fig. 1;

Fig. 4 is a view similar to Fig. 3, but illustrating the auxiliary bed section in open, effective position;

Fig. 5 is an enlarged cross-sectional view taken substantially on the line 5—5 of Fig. 4;

Fig. 6 is a fragmentary front elevational view of the bed shown in Fig. 1, but illustrating a modified form of my invention; and

Fig. 7 is a top plan view of the bed as shown in Fig. 4 with certain parts broken away to disclose the construction thereof.

Referring now in detail to the drawings I have shown a twin couch or bed of the type shown and described in my said Patent 2,133,167, comprising a sliding bed section 20 adapted to be nestably disposed underneath a couch member, not shown in the present application, but which is designated by the numeral 11 in Fig. 3 of the drawings of my said prior patent.

The section 20 in this application corresponds to that designated by the numeral 22 in my said prior patent. The reason the couch member is not shown in the present application is because my invention is concerned only with an improved construction for the bed section which is adapted to be nested underneath the couch member.

The sliding section 20 comprises a top frame 21 and a bottom frame 22 disposed below and

aligned with the said top frame. The bottom frame 22 comprises side rails 23 and 24 interconnected by end rails 25 and 26 to form the rectangular frame 22. Each of rails 23 to 26 is preferably of angular cross-section, as shown. The top frame 21 comprises side rails 27 and 28 interconnected by ends rails 29 and 30 to form the rectangular frame 21. Fixed to the corners of the bottom frame 22 and extending upwardly therefrom are guide members 37, 38, 39 and 40 of angular cross-section. The said members 37 to 40 are provided with rollers 41 at the lower ends thereof to facilitate the movement of the bed section 20. Additional rollers 42 fixed to the bottom frame rails 23 and 24 and midway between the rollers 41 may be provided.

The following means are provided for so interconnecting the top and bottom frames 21 and 22 that the top frame 21 may be lowered from the position shown in full lines in Fig. 1, to the dotted line position 21'. A pair of rigid members 45 and 46 are pivotally mounted by the pivots 47 at the lower ends thereof to each of the rails 23 and 24 of the bottom frame 22. The upper ends 20 of the members 45 and 46 are provided with pin projections 48, angularly disposed with respect to the members 45 and 46 and freely received in elongated slots 49 in the rails 27 and 28 of the top frame 21.

30 It is thus seen from the above described construction that the top frame 21 will be held at all times in attachment with the bottom frame 22 and cannot be accidentally lifted therefrom, as would be the case in some types of bed constructions heretofore manufactured. At the same time it is noted that the top frame 21 may be lowered to the dotted line position between the guide members 37 to 40, by rotating the members 45 and 46 in a counterclockwise direction as viewed from Fig. 1. The slots 49 are of sufficient length to allow free lateral movement of the pins 48 therein. Bars 50 parallel to the rails 23 and 24 of the bottom frame 22 and spaced therefrom, serve to interconnect each pair of members 45 and 46 to cause unitary movement of the said pairs of leg members 45 and 46.

Also interconnecting each pair of corresponding rails 23, 27 and 24, 28, are a pair of members 51 and 52 arranged in crossed relationship (see 50 Fig. 1) and having their upper ends pivotally fixed to the rails 27 and 28 by the pivots 53, while their lower ends are provided with pin projections 54 freely operating in the slots 55 of the frame rails 23 and 24.

55 A suitable handle member 56 is provided to

facilitate the rotational movement of the members 45 and 46 to lower and to raise the top frame 21. The handle member 56 may be rigidly fixed to one of the leg members, such as, for example, the member 46, as shown in Fig. 1.

The bed section 20 when not in use and when it is disposed underneath the couch section, as in my said Patent 2,133,167, is in collapsed position as shown by the dotted lines in Fig. 1. After the section 20 has been slidably moved outwardly from underneath the couch section, the handle 56 is moved from its dotted line position 56' to its full line position. This causes the pairs of members 45 and 46 to rotate on their pivots 47, in a clockwise direction to raise the top section 21. Rigid angle members 57 and 58 interconnect the pairs of members 45 and 46 respectively.

It is noted that the slots 49 in the rails 27 and 28 and the slots 55 in the rails 23 and 24 limit the clockwise rotational movement of the pairs of members 45 and 46.

To facilitate movement of the pairs of leg members 45 and 46 by normally urging the clockwise rotation thereof, I provide a pair of springs 60, one end of each spring being fixed to the rails 23 and 24, and the opposite ends of the said springs 60 being fixed to the member 45.

It is thus seen from the above description that the springs 60 will lie along one leg of the channelled rails 23 and 24 when the section 20 is in collapsed position, and thereby will be in a protected position. The direction of the pulling force of the springs 60 will maintain the top frame 21 of the section 20 in raised position.

In accordance with my invention I have provided the top frame 21 with an auxiliary frame 61 hingedly connected to the frame 21 by the hinges 62, which is adapted to be moved from the collapsed position shown in Figs. 1, 2 and 3, to the open position shown in Figs. 4 and 8, to provide additional sleeping space. The auxiliary frame 61 comprises a pair of side rails 63 and 64, interconnected by end rails 65 and 66 to form a substantially rectangular frame 61 of the same size as the frame 21. The frames 21 and 61 are provided with customary springs S and S'. To properly support the frame 61 in open position a pair of leg members 67 are pivotally mounted at one of the ends thereof, on the end rails 65 and 66, by the pivots 68. Links 69 pivotally interconnected to the legs 67 and to the rails 29 and 30 in the customary manner, by the pivots 70 and 71, serve to automatically swing the legs 67 to open or collapsed position, as desired. The links 69 are also constructed and arranged so as to serve as a safety means to prevent the lowering of the frame 21 while the auxiliary frame 61 is open. If an attempt is made to turn the handle 56 inwardly to lower the frame 21 the links 69 will abut the uprights 38 and 39 as shown in Fig. 4. If desired, extensions 72 may be fixed to the members 38 and 39 to more definitely lie in the path of movement of the links 69.

In addition to the safety device just described for preventing the lowering of the top frame 21 while the auxiliary frame 61 is in open position, I have provided, in accordance with my invention, means to prevent the movement of the auxiliary frame 61 to open position when the top frame 21 is in its lowered position. To this end I provide a rigid plate 75 fixed to the rail 64 of the frame 61. Fixed to and movable with the handle 56, is a latch member 76 provided with a notch 77 adapted to have received therein the plate 75, when the auxiliary frame 61 is in the

lowered position shown by the dotted lines in Fig. 1 of the drawings. In such latter position it is not possible to pivotally move the auxiliary frame 61 until the top frame 21 has been raised to effective position for use.

While in Figs. 1 and 2 I have shown the preferred position for the springs 60, it is understood that in accordance with my invention the springs 60 may be effectively positioned as shown in Fig. 7. In this form of my invention a spring 80 or a plurality of such springs, may be employed to normally urge the rotational movement of the leg members 45. The spring 80 is fixed at one end thereof to a cross angle bar 81 interconnecting the two members 45 while the opposite end of the spring 80 is fixed to a cross angle bar 82 transversely interconnecting the bottom rails 23 and 24. The structure above described is so designed that normally the links 50 clear the cross bar 81. However, if it is found necessary to insure such clearance, then suitable notches may be provided in the cross bar 81 to receive the links 50, in any well known manner.

In accordance with the provisions of the patent statutes, I have herein described the principle and operation of my invention, together with the apparatus and the construction which I now consider to represent the best embodiment, but I desire to have it understood that the construction shown is only illustrative and that the invention can be carried out by other means. Also, while it is designed to use the various features and elements in the combination and relation described, some of these may be altered and others omitted without interfering with the more general results outlined, and the invention extends to such use.

Having described my invention, what I claim and desire to secure by Letters Patent is:

1. In a bed section of the character described the combination of a bottom frame, a top frame substantially in alignment therewith, each of said frames comprising side rails and end rails, each of the side rails of said top frame being provided with a pair of spaced slotted openings, a pair of leg members pivoted to each of the side rails of said bottom frame, each of such pair of leg members being interconnected by a link for simultaneous movement, said leg members being provided with pins freely movable in said slotted openings whereby said top frame may be lowered to substantially overlie said bottom frame upon pivotal movement of any one of said leg members and an auxiliary frame hingedly movable with respect to said top frame and adapted to overlie the same when in non-extended position, rigid upright members extending upwardly from said bottom frame, pivotally mounted leg members on said auxiliary frame and links interconnecting said last named leg members with said top frame, said upright members being so disposed as to lie in the path of movement of said links to prevent the lowering of the top frame while the auxiliary frame is in extended position.

2. In a bed section of the character described the combination of a bottom frame, a top frame substantially in alignment therewith, each of said frames comprising side rails and end rails, each of the side rails of said top frame being provided with a pair of spaced slotted openings, a pair of leg members pivoted to each of the side rails of said bottom frame, said leg members being provided with pins freely movable in said slotted openings whereby said top frame may be lowered to substantially overlie said bottom frame upon pivotal movement of said leg members, a manu-

ally manipulative handle member for moving said leg members, an auxiliary frame hingedly attached and movable to extended position with respect to said top frame and adapted to overlie the same when in closed position, said auxiliary frame having a side rail and means for preventing the pivotal movement of said auxiliary frame to extended position when said top frame is in lowered position, said last named means comprising a plate fixed to said side rail of said auxiliary frame, and a projecting member having a notch, movable with said handle and adapted to auto-

matically receive therein said plate when said top frame is in lowered position to lock the same.

3. In a bed section of the character described, the combination according to claim 2 in which 5 rigid upright members extend upwardly from the bottom frame, and in which leg members are pivotally mounted on said auxiliary frame, links interconnecting said last named leg members with said top frame, said upright members being 10 so disposed as to lie in the path of movement of said links to prevent the lowering of the top frame while the auxiliary frame is in extended position.

MEYER GURSKY.
